ELECTRICAL CABLE MANUFACTURE

Florimond Aristide Jules Douchet, Paris, France, assignor to Societe Alsacienne de Constructions Mechaniques S. A., Paris, France

Application July 10, 1951, Serial No. 236,036

Claims priority, application France July 21, 1950

7 Claims. (Cl. 226—23)

There exist electric cables in which the insulation between the conductors consists of an insulating mineral substance which is usually magnesium oxide or any other insulating substance of analogous physical characteristics.

The pulverulent nature of the insulators used in these cables leads to the placing of the assembly of conductors and the insulating material within a tubular metallic sheath which can, if desired, also be used for conducting electric current.

Methods are known for packing the powdered insulating material. These methods include dehydrating the powdered material and introducing it into the top of a vertical sheath by joltings or repeated falls of a weight which is subjected to vertical reciprocation and which conforms to the section of the workpiece formed by the sheath and the conductors. A certain clearance is provided to allow the insulating material to pass beneath the weight.

The present invention has as its object a process and a device for consolidating the powdered insulating material in electric cables having one or more conductors. By means of the present invention, the proper consolidation is ensured by jolts which are preferably of high frequency and which are impressed upon the assembly formed by the sheath, the conductors and the insulating material by a vibrator, and in which a heavy mass is applied to the upper part of the insulating material.

Preferably, the heavy weight includes a number of weights subjected to a vertical reciprocation, bearing on the insulating material and suspended from one of the vertical runs of a cable the other vertical run of which supports a counterweight in such a way as to exert on the insulating material a pressure which is practically constant whatever may be the height of the insulating material within the sheath and to maintain the weights continuously in bearing contact with the insulating material.

The invention itself will be best understood, both as to its construction and its method of operation, from the following description of specific embodiments when read in connection with the accompanying drawings, in which:

Figure 1 is a diagrammatic longitudinal cross-sectional view of a device constructed in accordance with the present invention;

Figure 2 is a sectional view taken on the line II—II of Figure 1; and

Figure 3 is a sectional view similar to that of Figure 2 for a cable having two inner conductors.

Referring now to Figs. 1 and 2, a work-piece is formed of a metallic sheath 1 and an inner conducting wire 2 which is disposed and maintained along the axis of the sheath 1. The work-piece 1, 2, is mounted on a vibrator 3 having a frequency of, for example, 50 cycles per second, which is shown diagrammatically as a rotor 4 with an out-of-balance portion 5 and which rests on springs 6 on the ground. The mineral insulating material 7 is fed through the top of the sheath 1 by means of a distributor 8.

Two weights 9, the vertical median section of which has the shape of a triangle, the lower oblique side of which has a slope preferably substantially equal to the natural

2

angle of repose of the substance 7 (Figure 1), have a semi-circular horizontal median section. The two horizontal sections of the weights 9 together occupy the whole section of the internal part of the sheath 1 not occupied by the conductor 2. It can be seen that the lower faces of the weights 9 form an acute angle with the inner conductor 2 and that the tips of the lower faces of the weights adjacent the sheath 1 are lower than the tips of the weights adjacent the conductor 2.

5 The weights 9 are attached by rods 10, shaped as circular arcs in order to give them more resistance to bending, to a balance beam 11 at two points 13 equidistant from the center of oscillation 12 of the balance beam 11. Oscillatory movement is impressed upon the latter by a transmission represented diagrammatically by a connecting rod 14 attached to an eccentric point in a disc 15 rotating about its axis.

10 The assembly consisting of weights 9, rods 10, balance beam 11 and driving mechanism 14 and 15, is suspended from a cable 16 which passes over pulleys 17. The cable 16 supports, at the end of its other vertical run, a counter-weight 18.

15 The described device operates as follows:

Under the action of the high frequency impulses communicated to the work-piece 1, 2, and to all that it contains, the insulating material 7 fed in a regular manner by the distributor 8 is subjected to a consolidating effect. The mass of the weights 9 exerts a reaction on the material 7 which is thus transformed into a compact block forming a solid bearing for that weight 9.

20 During this time, the other weight 9 is progressively lifted by the balance beam 11 and the intermediate rods 10.

25 The free space thus formed beneath these weights 9 is progressively filled by the powder which showers into the sheath 1.

30 As previously mentioned, the insulating material is consolidated by the action of the vibrator 3. When the weight 9 under consideration has completed its upward stroke, it has a sufficiently good support beneath it for the preceding reasoning to be again applicable.

35 The assembly 9, 10, 11, 14 and 15, therefore rises gradually, constantly bearing on the compact block of powder which forms progressively beneath it.

40 As this process continues, the degree of compactness is determined by the reactions of the weights 9 and, therefore, by the mass of the latter, and by the thrust of the assembly 9, 10, 11, 14, 15 which is regulated by the counterweight 18.

45 When the weights 9 have been lifted up as far as the upper part of the sheath 1, the filling is terminated and the work-piece: sheath 1, conductor 2, insulating material 7, is ready for the subsequent drawing operation.

50 In the case of a single conductor 2, the assembly of the weights 9 can also be given a rotary movement about the vertical axis formed by the conductor 2.

55 Naturally, the present invention is not limited to the process and apparatus described above.

60 Thus, for example, the apparatus can be used for cables having several inner conductors 2 by simple modification of the section of the weights 3, as can be seen in Figure 3.

65 It may finally be stated that the invention covers also the use, with or without a jolting device, of a number of weights capable of being displaced one relatively to the other, so as to leave between them at least at certain instants a space through which the insulating material can pass beneath the weights.

70 1. An apparatus for consolidating powdered insulating material in an electric cable having an external sheath and at least one conductor to be separated from said

sheath by said insulating material, comprising, in combination, means for supporting vertically the cable, said supporting means making contact with said cable at the lowermost cross-section thereof; means for imparting vibrations to said supporting means and said cable supported by the same; two weights of triangular cross section adapted to be arranged in said cable alongside each other on opposite sides of said conductor so as to act on separate portions of said powdered insulating material filling said cable; and means for imparting to said weights, respectively, alternative motions out of phase with one another, whereby one of said weights compresses said powdered insulating material in said cable while the other of said weights is ineffective, and vice versa, the lower faces of said weights forming an acute angle with said conductor, the tips of the faces of said weights adjacent said cable being lower than the tips of said weights adjacent said conductor.

2. An apparatus for consolidating powder insulating material in an electric cable having an external sheath and at least one conductor to be separated from said sheath by said insulating material as in claim 1, in which the acute angle formed by said lower faces of said weights and said conductor is substantially equal to the angle of the natural slope of the insulating material to be compressed.

3. An apparatus for consolidating powdered insulating material in an electric cable having an external sheath and at least one conductor to be separated from said sheath by said insulating material, comprising, in combination, means for supporting vertically the cable, said supporting means making contact with said cable at the lowermost cross-section thereof; means for imparting vibrations to said supporting means and said cable supported by the same; two weights of triangular cross section each having a lower face forming an acute angle with a horizontal plane, the tips of the faces of said weights adjacent said cable being lower than the tips of said weights adjacent said conductor, said weights being adapted to be arranged in said cable alongside each other on opposite sides of said conductor so as to act on separate portions of said powdered insulating material filling said cable; and means for imparting to said weights, respectively, alternative motions out of phase with one another, whereby one of said weights compresses said powdered insulating material in said cable while the other of said weights is ineffective, and vice versa.

4. An apparatus for consolidating powdered insulating material in an electric cable having an external sheath and at least one conductor to be separated from said sheath by said insulating material, comprising, in combination, means for supporting vertically the cable, said supporting means making contact with said cable at the lowermost cross-section thereof; means for imparting vibrations to said supporting means and said cable supported by the same; two weights of triangular cross section adapted to be arranged in said cable alongside each other on opposite sides of said conductor so as to act on separate portions of said powdered insulating material filling said cable, each of said two weights having a lower face forming an acute angle with said conductor, the tips of the faces of said weights adjacent said cable being lower than the tips of said weights adjacent said conductor; two rods supporting said weights; and means for driving said rods, said driving means imparting to said rods, respectively, alternative motions out of phase with one another, whereby one of said weights compresses said powdered insulating material in said cable while the other of said weights is ineffective, and vice versa.

5. An apparatus for consolidating powdered insulating material in an electric cable having an external sheath and at least one conductor to be separated from said sheath by said insulating material, comprising, in combination, means for supporting vertically the cable, said supporting means making contact with said cable at the

lowermost cross-section thereof; means for imparting vibrations to said supporting means and said cable supported by the same; two weights of triangular cross section adapted to be arranged in said cable alongside each other on opposite sides of said conductor so as to act on separate portions of said powdered insulating material filling said cable, each of said two weights having a lower face forming an acute angle with said conductor, the tips of the faces of said weights adjacent said cable being lower than the tips of said weights adjacent said conductor; two rods supporting said weights; and means for driving said rods, said driving means imparting to said rods, respectively, alternative motions out of phase with one another, whereby one of said weights compresses said powdered insulating material in said cable while the other of said weights is ineffective, and vice versa, said imparting means including a balance beam having two arms connected, respectively, to said rods, and a motor imparting to said balance beam a rocking motion in alternative opposite directions about the center of said balance beam.

6. An apparatus for consolidating powdered insulating material in an electric cable having an external sheath and at least one conductor to be separated from said sheath by said insulating material, comprising, in combination, means for supporting vertically the cable, said supporting means making contact with said cable at the lowermost cross-section thereof; means for imparting vibrations to said supporting means and said cable supported by the same; two weights of triangular cross section adapted to be arranged in said cable alongside each other on opposite sides of said conductor so as to act on separate portions of said powdered insulating material filling said cable, each of said two weights having a lower face forming an acute angle with said conductor, the tips of the faces of said weights adjacent said cable being lower than the tips of said weights adjacent said conductor; means for imparting to said weights, respectively, alternative motions out of phase with one another, whereby one of said weights compresses said powdered insulating material in said cable while the other of said weights is ineffective, and vice versa; at least one pulley; a cable passing over said pulley and having two ends, one of said ends of said cable being attached to said imparting means; and a counterweight attached to the other end of said cable.

7. An apparatus for consolidating powdered insulating material in an electric cable having an external sheath and at least one conductor to be separated from said sheath by said insulating material, comprising, in combination, means for supporting vertically the cable, said supporting means making contact with said cable at the lowermost cross-section thereof; means for imparting vibrations to said supporting means and said cable supported by the same; two weights of triangular cross section adapted to be arranged in said cable alongside each other on opposite sides of said conductor so as to act on separate portions of said powdered insulating material filling said cable, each of said two weights having a lower face forming an acute angle with said conductor, the tips of the faces of said weights adjacent said cable being lower than the tips of said weights adjacent said conductor; two rods supporting said weights; means for driving said rods, said driving means imparting to said rods, respectively, alternative motions out of phase with one another, whereby one of said weights compresses said powdered insulating material in said cable while the other of said weights is ineffective, and vice versa, said imparting means including a balance beam having two arms connected, respectively, to said rods, and a motor imparting to said balance beam a rocking motion in alternative opposite directions about the center of said balance beam; at least one pulley; a cable passing over said pulley and having two ends, one of said ends of said cable being attached to said imparting means; and a counterweight attached to the other end of said cable.
